UNITED STATES PATENT OFFICE.

FRANK L. HOLT, OF WICHITA, KANSAS.

GAGE-COCK.

1,177,034.

Specification of Letters Patent. Patented Mar. 28, 1916.

Application filed January 8, 1914. Serial No. 811,104.

To all whom it may concern:

Be it known that I, FRANK L. HOLT, a citizen of the United States, residing at Wichita, in the county of Sedgwick and State of Kansas, have invented certain new and useful Improvements in Gage-Cocks, of which the following is a specification.

This invention relates to improvements in gage cocks for boilers, and one object is to produce a device of this character which can be cleaned or repaired without materially affecting the boiler pressure.

Another object of the invention is to provide a device in which is eliminated as far as practicable any danger of injury from escaping steam.

A still further object is to improve the valve and valve seat elements of this type of cock so that the valve seat may be repeatedly dressed to accommodate the valve and the latter may be conveniently turned upon its seat for cleaning purposes without disturbing any of the other parts of the device.

With these objects in view the invention consists in certain novel and peculiar features of construction and organization as hereinafter described and claimed, and in order that it may be fully understood reference is to be had to the accompanying drawing, in which—

Figure 1, is a longitudinal section through a gage cock embodying the features of my invention. Fig. 2, is a transverse section on the line II—II of Fig. 1.

Referring to the drawing, the device comprises a tapered tubular member 2 having suitable external threads for tightly fitting the same through the boiler head plate 4, the passage 8 through this member 2 being controlled by a valve plug 6. The outer end of the member 2 is externally threaded for engagement by the inner end of a valve casing 10. Within this casing operates a valve stem 12 which threadedly engages the outer end of said casing. The inner end of the valve stem is of larger diameter than its threaded end and is provided with a packing ring 14, it being understood that the valve stem must be inserted through the inner enlarged end of the casing 10 and cannot be withdrawn through the outer end of the casing, thus guarding against careless operation of the valve allowing steam to exhaust directly toward the operator. An outlet tube 16 is provided in communication

with the valve chamber 18 at the inner end of the valve casing 10.

The outer end of the passage 8 is enlarged and adapted to receive the shank of a plug 20, the head of which operates as a valve seat for the head 22 of a needle valve, the shank 24 of which extends axially through the stem 12. The head 22 is tapered in both directions and ground for fitting both the valve seat and the inner end of the stem 12. To guard further against any leakage around the shank 24 when the valve is off its seat, packing 26 is fitted in the outer end of the stem 12 about said shank and retained in place by the washer 28 which serves also to hold a handle 30 on the outer squared end of the stem 12. The shank 24 of the valve is provided with a kerf 32 in its outer end to permit the use of a suitable tool for turning the valve and a pin 34 for retaining the washer 28 in place and effecting outward movement of the needle valve when the valve stem 12 is unscrewed.

As it is advisable frequently to test the water gage, the valve 6 will be normally open. To make the test, the handle 30 is turned to unseat the valve 22, and water or steam, as the case may be, will be allowed to escape in a lateral direction by way of the outlet tube 16.

Provision of the kerf 32 allows the valve 22 to be turned to clean the contact between it and the valve seat 20, without removal of any of the parts or disturbing their adjustment. In case it should be necessary to remove the casing 10 to repair the valve, the valve 6 is closed, after which the remaining members can be conveniently repaired, and the plug 20 provides a projecting valve seat which can be dressed down indefinitely to accommodate the point of the valve head 22. Whenever necessary to clean the passage 8, this may be done after the other parts have been detached by opening the valve plug 6 and inserting a bent wire through the passage, the bent wire being used because it enables the operator to perform the cleansing operation without danger of being scalded.

From the foregoing it will be apparent that I have produced a gage cock possessing the features of advantage enumerated as desirable and I wish it to be understood that while I have illustrated and described what now appears to me to be the preferred embodiment of the same I do not desire to be

2
restricted to the exact details of construction and organization shown and described, but reserve the right to make all changes falling within the spirit and scope of the appended claim.

I claim:

A gage cock comprising a tubular member for screwing into a boiler, provided with a valve intermediate the ends of its passage, 10 a tubular headed plug screwed into the outer end of the said member so that its passage communicates with that of the said tubular member and provided with a valve-seat at its outer end, a casing secured on 15 the outer end of the tubular member and inclosing the portion of the plug projecting beyond the outer end of said member, and provided with a laterally-projecting outlet tube, an inwardly-facing internal annular tube, an inwardly-facing internal annular 20 shoulder, and internal threads outward of said shoulder, a tubular externally-threaded valve stem engaging the internal threads of the said casing and enlarged inward of the shoulder of said casing so as to be incapable 25 of being withdrawn outwardly therefrom

and provided beyond the outer end of the casing with a turning handle, a packing between the enlarged portion of said stem and the surrounding portion of the casing to prevent escape of steam or water around 30 the threaded portion of the said stem, a needle valve bearing against the inner end of said tubular stem and adapted to engage the valve-seat of the said plug, and provided with a shank journaled in and extending 35 through and beyond the bore of the tubular valve stem, a packing between the said shank and the tubular valve stem to guard against leakage through the latter, a washer fitting on the said shank and engaging the outer end of the tubular valve stem, and means secured to the shank and holding the washer in position.

In testimony whereof, I affix my signature, in the presence of two witnesses.

FRANK L. HOLT.
